(57) **CLAIM**

The ornamental design for a locking washer, as shown and described.

DESCRIPTION

FIG. 1 is a top perspective view of a locking washer according to my new design;

FIG. 2 is a side view thereof;

FIG. 3 is a top plan view thereof;

FIG. 4 is a bottom plan view thereof;

FIG. 5 is a top perspective view of a second embodiment of a locking washer according to my new design;

FIG. 6 is a side view thereof;

FIG. 7 is a top plan view thereof; and,

FIG. 8 is a bottom plan view thereof.

CERTIFICATE OF CORRECTION

PATENT NO. : Des. 602,349 S
APPLICATION NO. : 29/323456
DATED : October 20, 2009
INVENTOR(S) : Andersson

Page 1 of 6

It is certified that error appears in the above-identified patent and that said Letters Patent is hereby corrected as shown below:

Delete Title page, illustrating a figure(s), and substitute therefor, a new Title page illustrating a figure(s). (attached)

Delete drawing sheets 1-4, and substitute therefor, drawing sheets 1-4. (attached)

Signed and Sealed this

Thirtieth Day of March, 2010

David J. Kappos
Director of the United States Patent and Trademark Office
